R. W. HARDIE

METHOD OF HUMIDIFYING AIR

Filed Oct. 8, 1924

INVENTOR

Robert W. Hardie

UNITED STATES PATENT OFFICE.

ROBERT W. HARDIE, OF FANWOOD, NEW JERSEY.

METHOD OF HUMIDIFYING AIR.

Application filed October 8, 1924. Serial No. 742,341.

To all whom it may concern:

Be it known that I, ROBERT W. HARDIE, a citizen of the United States, residing at Fanwood, in the county of Union and State of New Jersey, have invented new and useful Improvements in Methods of Humidifying Air, of which the following is a specification.

This invention relates to methods of increasing the relative humidity of an indoor atmosphere, and is especially designed for use in dwellings, apartments, banks, stores, and other buildings of a similar character.

The relative humidity of an indoor atmosphere can be increased only by the addition thereto of water, in one form or another, generally by absorption, water sprays, steam, or vapor.

The present invention relates to a vapor method.

The term "vapor" is used herein, in connection with the present invention in the same sense as used by heating engineers generally, that is, steam at about or under 25 eight ounces pressure.

Vapor has heretofore been used as a means for increasing the relative humidity of an indoor atmosphere, and hot air heaters have been provided with a water receptacle arranged within the outer casing of the heater, or generator, and in their best forms supplied with an automatic water feed.

When so provided, such heaters are in a considerable extent successful in use in respect to humidifying effects. Such means, however, are adapted for use only with hot air heaters, and are deficient in that no provision is made, or can be made, for regulating or controlling the amount of vapor discharged into the atmosphere.

Efforts have also been made to supply vapor to an indoor atmosphere by placing a body of water within an open receptacle and subjecting the water to heat supplied from a steam coil, or chamber, placed within the receptacle, and connected with a steam or vapor generator.

The use of such means, however, is limited to steam and vapor heating systems, and such means have proved unsuccessful and to a large extent impracticable, for the reason among others, that the amount of vapor discharged from the receptacle can not be regulated and controlled.

This invention has for its main objects, to produce a method of humidifying air that may be readily applied independently of the heating system of a building, that is adapted to generate and discharge vapor in such condition that it may be readily absorbed by and become diffused into the indoor atmosphere of a building in such a manner as to avoid condensation on objects adjacent the place of discharge, and that is adapted to regulate and control, within vapor limits, the quantity of vapor discharged into an indoor atmosphere during a predetermined period of time.

These and other objects of the invention hereinafter stated, are accomplished in the manner hereinafter fully described.

In carrying out the invention, a desired quantity of water is confined within a closed receptacle, and is converted into vapor by the application of a heating element thereto.

In order that the application of the heating element to the water shall produce vapor instead of steam, the heating element is coordinated with the quantity of water within the receptacle, so that the predetermined maximum feed or supply of the heating element will be sufficient to produce vapor only, and not steam, within the receptacle, that is, vapor in the sense of steam at about eight ounce pressure. That is accomplished by regulating or apportioning the quantity of heating element supplied to a given quantity of water so that the maximum quantity of heating element supplied will not heat the water above a temperature of approximately 210° F.

With the maximum supply of heating element so established and correlated with the constant quantity of water within the

receptacle, the quantity of vapor produced within vapor limits may be regulated and controlled by decreasing the supply of heating element, at any desired point below its 5 maximum of approximately 210° F and above 180° F.

The maximum supply of the heating element required to produce the desired amount of vapor may be the absolute maximum supply of the heating element capable of being produced in the circumstances, or it may be any proportion thereof established as the maximum feed or supply of heating element, that can be applied to the water in the receptacle without producing steam to an objectionable extent above eight ounce pressure:

After the necessary quantity of heating element has been coordinated with the supply of water within the receptacle so as to produce vapor, that is, steam of about eight ounce pressure, the vapor is dispersed into the atmosphere by being discharged from the receptacle in jets, spaced apart or other distributing means, so that it may be readily absorbed by the atmosphere without condensing on objects near the place of discharge.

And to aid in enabling the vapor to be readily absorbed by the atmosphere, the initial pressure of the vapor is subdued or muffled so that the vapor will go into the atmosphere in as near as possible atmospheric condition.

The following example will serve to show how the heating element may be coordinated with a constant quantity of water, so as to produce vapor instead of steam, using gas as a heating element, and how the supply of vapor may be regulated and controlled.

Assuming that it requires one thousand heat units to vaporize a pint of water, and assuming that the gas used has a value of 600 B. T. U. s per cubic foot of gas, and that the burner supplying the gas has a capacity of delivering fifteen cubic feet of gas an hour, and is operating under sixty per cent efficiency, about fifty-nine hundred B. T. U. s will be supplied per hour to the body of water within the water container, to which the burner is applied, which would vaporize approximately three quarts of water per hour.

To vaporize three quarts of water per hour the maximum quantity of heating element applied to the water therefore would be the equivalent of gas supplied by a fifteen foot burner operating under sixty per cent efficiency of the full capacity of the burner.

The quantity of vapor developed within such maximum limit may be varied and controlled by reducing the quantity of heating element supplied, in this case gas.

And if a burner is used having a greater

capacity than fifteen feet an hour, the supply of gas to the burner may be reduced to the equivalent of a flow of fifteen cubic feet an hour, and the maximum supply may be established at that point on such a burner 70 by marking the inlet valve of the burner. The marking would then indicate the maximum feed to produce that amount of vapor; and to regulate and control the supply of vapor below the absolute maximum limit 75 of the burner, or a set marking on a larger burner, the supply may be regulated by reducing the supply of gas below said absolute or established maximum, by adjusting the valve connected with the burner.

In estimating the quantity of vapor desired to be discharged into the atmosphere, allowance should be made for recondensing of part of the vapor within the receptacle, especially if no insulating material 85 surrounds the receptacle; and allowance should also be made for a certain amount of loss by friction in passing through discharge pipes leading from the receptacle, if placed in the basement of a building, to the place 90 of discharge on a floor above.

The vapor generated should therefore have sufficient initial pressure to cause the vapor to rise the height of one story of a building if the main apparatus is placed in the basement of a building; or sufficient pressure to cause the vapor to flow laterally, if the vapor generating apparatus is placed on the same floor as the discharge, as in the case of apartments.

To that end the vapor generated in the tank or container should be of a slightly higher pressure than at the place of discharge into the indoor atmosphere.

The method may be carried out by means of the apparatus illustrated in the accompanying drawing, wherein a tank or container 1 is shown having a water inlet pipe 2, connected with the lower end of the tank and with a water supply receptacle 3, which in turn is connected with a main water supply pipe 4.

The end of the supply receptacle 3, is provided with a water inlet valve of ordinary construction, not shown, which is automatically operated by the usual float 5.

The tank 1 is mounted upon a base 6, provided with lugs 7, which support the lower end of the tank.

A gas burner is shown supported within the base in close proximity to the lower head of the tank 1, and is connected with a gas inlet pipe 9, which may if desired be secured to the base 6 by means of a threaded engagement with a plate 10 attached to said base.

A valve 11 is connected with the inlet pipe 9 so as to regulate and control the amount or supply of gas delivered to the burner 8.

By means of such construction water at a 130

predetermined level and quantity, may be constantly maintained, and automatically supplied within the tank 1, and any desired amount of gas as a heating element may be applied to the water within the tank by regulating the burner valve accordingly.

The upper end of the tank 1 is supplied with one or more discharge outlets 12, which are connected with a discharge pipe 13.

10 The discharge pipe 13 is connected at its upper end with a discharge head 14, and if desired, an outer shell or tube 15 may be arranged outside the pipe 13, and supported on or connected with a base 16, to give a 15 finished appearance to the discharge head connections.

The discharge head 14 is provided with apertures 17, by means of which the vapor is discharged from the head in the form of 20 jets, spaced apart, and the upper end of the head is provided with a top or cap 18.

If desired, the vapor may be muffled, so as to further aid in enabling the vapor to be readily absorbed by the atmosphere, as by 25 means of wire mesh 19, placed against the inner wall of the head over the openings 17, and held in place by means of a spring ring 20, bearing against the said wire mesh to hold the mesh in position.

30 Such inner ring is provided with openings 21 registering with the openings 17 of the discharge head.

In the apparatus shown, the vapor generator is designed to be placed in the basement of a building and carried up to the next floor by means of one or more discharge pipes extending upward from the generator.

Where the apparatus is designed for use 40 in apartments, or houses, such as one story houses, the apparatus may be arranged on the same floor as the discharge heads and in such cases the vapor is carried laterally.

If desired, a thermostat may be placed 45 in the water of the tank and connected with the valve controlling the quantity of heating element delivered to the burner and regulated between 210° as the maximum limit and 180°.

50 The valve controlling the gas burner may be itself controlled, if desired, by a thermostatic control placed on the floor where the vapor is delivered into the atmosphere.

The construction of the apparatus shown 55 is no part of the present invention and other means having similar capabilities may be substituted therefor, if desired, especially the means of muffling the initial pressure of the vapor, so that the vapor may pass gently 60 into the atmosphere.

Having determined the quantity of heat necessary to produce the maximum quantity of vapor desired, the quantity of water placed in the receptacle is correlated with 65 the maximum quantity of heating element

so that the maximum quantity of heating element supplied will heat the water in the receptacle to a temperature slightly below the boiling point—about 210° F.

If the quantity of water is too great, the 70 heating element will be absorbed in merely heating the water instead of producing vapor of the required kind; and if the quantity of water is too small, the water will boil and produce steam heavily laden 75 with water, and not in a condition to be absorbed by the atmosphere.

I have found that about seven gallons of water cooperating with a fifteen foot gas 80 burner operating under sixty percent efficiency, produces very satisfactory results.

A burner of larger capacity than that 85 actually required might be used for such purpose, but in such cases in order to operate to the best advantage, the valve connected with the burner should be set at an indicated maximum capacity adapted to heat the water to a temperature of 210° F. and so marked, and all adjustments made 90 below that limit.

It should be borne in mind that gas is of 95 different origins and is made of different mixtures, and varies in heat values, but the proportions stated will serve for ordinary purposes using manufactured gas. The corresponding value of natural gas may be readily ascertained.

What I claim as new is:

1. The method of humidifying air, consisting in maintaining a uniform quantity 100 of water within a closed receptacle, vaporizing said water by the application of a heating element thereto while maintaining the temperature of said water between 180° F. and 212° F., passing the vapor into an auxiliary receptacle, muffling the vapor so as to substantially remove its initial pressure, and diffusing the vapor into the atmosphere in restricted quantity.

2. The method of humidifying air, consisting in maintaining a uniform quantity 110 of water within a closed receptacle, vaporizing said water by the application of a heating element thereto while maintaining the temperature of said water below 212° F., passing the vapor into an auxiliary receptacle, muffling the vapor and thereby removing its initial pressure, and diffusing the vapor into the atmosphere by passing it 115 through restricted apertures.

3. The method of humidifying air, consisting in maintaining a uniform quantity 120 of water within a closed container, vaporizing said water by the application of a heating element thereto, regulating the quantity of heating element supplied so as to vary the temperature of said water between approximately 180° F. and 212° F., passing the vapor into an auxiliary receptacle, muffling the vapor to remove its initial pres- 130

sure, and diffusing the vapor into the atmosphere in restricted quantity.

4. The method of humidifying air, consisting in maintaining a uniform quantity of water within a closed receptacle, vaporizing said water by the application of a heating element thereto, regulating the quantity of heating element supplied, so as to vary

the temperature of said water between approximately 180° F. and 212° F., passing the vapor into an auxiliary receptacle, muffling the vapor to remove its initial pressure, and dispersing the vapor into the atmosphere.

ROBERT W. HARDIE.
